UNITED STATES PATENT OFFICE.

GEORGE S. BARKENTIN, OF NEW BRITAIN, CONNECTICUT, ASSIGNOR TO
P. & F. CORBIN, OF SAME PLACE.

DESIGN FOR A LATCH-CASE.

SPECIFICATION forming part of Design No. 19,442, dated November 26, 1889.

Application filed October 30, 1889. Serial No. 328,706. Term of patent 7 years.

To all whom it may concern.

Be it known that I, GEORGE S. BARKENTIN, a citizen of the United States, residing at New Britain, in the county of Hartford and State 5 of Connecticut, have invented and produced a new and original Design for a Latch-Case, of which the following is a specification, reference being had to the accompanying drawings, forming part thereof.

10 Figure 1 is a front elevation of a latch-case, showing my design. Fig. 2 is a plan view of the same, and Fig. 3 is a sectional view of the upper portion of said case on the line x x of Fig. 2.

15 The leading feature of my design consists in raised block-like groups of parallel beads alternating from vertical to horizontal, and series of curved ornaments extending vertically over the middle portion of the sides.

20 A A are the sides of my latch-case, and B the top. The sides are both alike, and are ornamented by vertical beads 4 at each edge, a parallel bead 5 near the back edge of the case, and a double vertical bead 6 nearer the 25 front edge of the case. On that side of the double bead 6 which faces the back edge of the case is a vertical series of curved ornaments 7, the same consisting of connected crescent-like figures with trefoils 8 at the junctions of

30 the several crescents. Between the bead 4 at the front edge of the case and the double bead 6 I arrange block-like groups of raised parallel beads 9, extending vertically, and intermediate block-like groups of raised beads 10, in

which the beads extend horizontally, thereby 35 forming block-like groups of alternating vertical and horizontal beads. The top and bottom plates are ornamented by two block-like series of raised parallel beads 11, extending lengthwise with said top and bottom, and an 40 intermediate boss or rosette 12, said top and bottom plates being convex and let in between the sides A A, as shown in Fig. 3.

What I claim is—

1. The design for a latch-case herein shown 45 and described, the same comprising the sides A A, the top and bottom B, said sides having the vertical beads, vertical series of curved ornaments, and block-like groups of alternating vertical and horizontal beads, said top and 50 bottom plates having the block-like groups of parallel beads 11 and intermediate rosette, as set forth.

2. In the design for a latch-case herein shown and described, the side A, having the 55 plain vertical beads, the vertical series of ornamental beads 7, and the block-like groups of alternating vertical and horizontal beads, as set forth.

3. In the design for a latch-case herein 60 shown and described, the top B, having the block-like groups of parallel beads and the intermediate rosette 12, as set forth.

GEORGE S. BARKENTIN.
